US00D874328S

(12) **United States Design Patent** (10) **Patent No.:** **US D874,328 S**
(45) **Date of Patent:** **** Feb. 4, 2020**

(54) **GEMSTONE**

(71) Applicant: **BONOLI S.R.L.**, Forlì' (IT)

(72) Inventor: **Massimiliano Bonoli**, Forlimpopoli (IT)

(73) Assignee: **BONOLI S.R.L.**, Forlì (IT)

(**) Term: **15 Years**

(21) Appl. No.: **29/671,297**

(22) Filed: **Nov. 26, 2018**

Related U.S. Application Data

(62) Division of application No. 29/600,161, filed on Apr. 10, 2017.

(30) **Foreign Application Priority Data**

Oct. 10, 2016 (EM) 003412881

(51) **LOC (12) Cl.** **11-01**

(52) **U.S. Cl.**

USPC **D11/91**

(57) **CLAIM**

I claim, the ornamental design for a gemstone, as shown and described.

DESCRIPTION

The file of this patent contains at least one photograph executed in color. Copies of this patent with color photograph(s) will be provided by the Office upon request and payment of the necessary fee.

FIG. 1 is a perspective view of a first embodiment of a gemstone, showing my new design;

FIG. 2 is a bottom view thereof;

FIG. 3 is a left side view thereof, the opposite side view being a mirror image thereof;

FIG. 4 is a top view thereof;

FIG. 5 is a front view thereof;

FIG. 6 is a rear view thereof;

FIG. 7 is a perspective view of a second embodiment of the gemstone, showing my new design;

FIG. 8 is a front view thereof;

FIG. 9 is a rear view thereof;

FIG. 10 is a top view thereof;

FIG. 11 is a left side view thereof, the opposite side view being a mirror image thereof;

FIG. 12 is a bottom view thereof;

FIG. 13 is a perspective view of a third embodiment of the gemstone, showing my new design;

FIG. 14 is a front view thereof;

FIG. 15 is a left side view thereof, the opposite side view being a mirror image thereof;

FIG. 16 is a top view thereof;

FIG. 17 is a rear view thereof; and,

FIG. 18 is a bottom view thereof.
